Primary Examiner — Jennifer Rivard

(57) **CLAIM**

The ornamental design for a combined electric shaver and massager, as shown and described.

DESCRIPTION

FIG. 1 is a top-front-left perspective view of a combined electric shaver and massager showing my new design; FIG. 2 is a bottom-rear-right perspective view thereof; FIG. 3 is an enlarged front elevational view thereof; FIG. 4 is an enlarged rear elevational view thereof; FIG. 5 is a left elevational view thereof; FIG. 6 is a right elevational view thereof; FIG. 7 is a top plan view thereof; and, FIG. 8 is a bottom plan view thereof. The broken lines illustrate portions of the combined electric shaver and massager and form no part of the claimed design.

1 Claim, 8 Drawing Sheets(56)
